UNITED STATES PATENT OFFICE.

LEO EHRLICH, OF ST. LOUIS, MISSOURI, ASSIGNOR TO THE AMERICAN ROLL PAPER COMPANY, OF SAME PLACE.

ROLL-PAPER HOLDER AND CUTTER.

SPECIFICATION forming part of Letters Patent No. 423,745, dated March 18, 1890.

Application filed February 13, 1888. Serial No. 263,796. (No model.)

To all whom it may concern:

Be it known that I, LEO EHRLICH, of the city of St. Louis, in the State of Missouri, have invented a certain new and useful Improvement 5 in Roll-Paper Holders and Cutters, of which the following is a full, clear, and exact description, reference being had to the accompanying drawings, forming part of this specification, and in which—

10 Figure I is an elevation of my improved roll-paper holder and cutter. Fig. II is an end view. Figs. III and V are detail sections taken on line III III, Fig. I. Fig. IV is a detail top view.

15 My invention relates to certain improvements in a roll-paper holder and cutter for holding and cutting wrapping-paper; and it consists in features of novelty hereinafter fully described, and pointed out in the claims.

20 Referring to the drawings, 1 represents a base to which are secured standards 2.

3 represents a roller having gudgeons or journals 4, bearing on tramways 5 of the standards 2, and 6 represents the paper on 25 the roller.

7 represents a knife secured to the outer ends of the tramways 5, and it is preferably provided with a toothed cutting-edge, as shown in Fig. I, though it may have a plain cutting-edge, if desired.

8 represents a small guide-roller journaled 30 in the tramways 5, and against which the paper bears, and is held by a spring 9. My preferred means of constructing this spring is to wind its respective ends around a pin or shaft 10, as shown at 11, and extend the central portion upward beneath the roller. To assist the spring in moving the roller, the tramways 5 may be inclined, as shown in Fig.

40 II, so that the roller will be supported on an inclined bearing and have a tendency to move toward the roller 8.

12 represents a second guide-roller located 45 near the guide-roller 8 and parallel thereto, and between these rollers the paper passes, as shown in Figs. II and III. The gudgeons of the roller 12 preferably fit in inclined grooves 13 in the tramways 5, so that it can be removed, if desired, in first placing the

50 paper between the rollers. The knife 7 is located a short distance from these rollers, and as the desired amount of paper is pulled through it is moved downward on the knife

and cut off. The portion 20 of the paper between the rollers and the knife will then spring 55 up into the position shown in Fig. II and afford an easy finger-hold when more paper is needed.

14 represents bars to hold the roller upon the tramways 5, and these are preferably 60 formed in one part with the tramways.

In Fig. V another means of threading the paper between the rollers 8 and 12 is shown. The paper is passed from above beneath the roller 8 and up between this roller and the 65 roller 12.

I do not herein claim the combination of the spindle carrying the paper roll and mounted in slotted bearings with a holding-roller arranged to be normally in contact with the 70 front of the periphery of the paper roll, knife, and spring-bars or levers.

I claim as my invention—

1. The combination of a suitable frame, a cutting-knife, tramways which support and 75 guide the roll of paper toward said knife, and a roller which prevents contact of the body of said roll of paper with said knife, substantially as described.

2. The combination of the standards having tramways forming supports for the paper-roller, guide-rollers journaled in the tramways, against one of which guide-rollers the paper-roller bears, and between which guide-rollers the paper passes, and a knife, substantially as and for the purpose set forth.

3. The combination of the standards having tramways forming supports for the paper-roller, guide-rollers journaled in the tramways and between which the paper passes, and a fixed knife secured to the tramways a distance from the guide-rollers, substantially as and for the purpose set forth.

4. The combination of the base, standards secured to the base and having tramways, 95 paper-roller bearing and moving upon the tramways of the standards, spring for moving the paper-roller, two guide-rollers journaled in the tramways, one of which guide-rollers is held in curved slots, and a knife 100 secured to the tramways, substantially as and for the purpose set forth.

LEO EHRLICH.

In presence of—

EDWD. S. KNIGHT,
JOS. WAHLE.
